his Attorney

UNITED STATES PATENT OFFICE.

FRANK E. CRAMPTON, OF CLEVELAND, OHIO.

VENTILATOR.

1,298,671.

Specification of Letters Patent.

Patented Apr. 1, 1919.

Application filed October 4, 1917. Serial No. 194,641.

To all whom it may concern:

Be it known that I, FRANK E. CRAMPTON, a citizen of the United States, residing at Cleveland, in the county of Cuyahoga and 5 State of Ohio, have invented certain new and useful Improvements in Ventilators, of which the following is a specification.

This invention relates to ventilators of the rotary type, and has for its main object 10 to provide a ventilator, which will greatly increase the velocity of air currents passing horizontally therethrough for producing siphonic action, and thereby exhaust air through a vertical pipe extending from a 15 building. This is accomplished in two ways—by making the horizontal air passage tapering toward its outlet and also by providing pockets for directing a part of this air within a cylindrical shell or chamber. 20 With the above and other objects in view as will be readily understood, the invention will be hereinafter fully described in connection with the accompanying drawings, which illustrate a preferred embodiment of 25 the same, and the novel features thereof will be distinctly pointed out in the appended claims.

In the different views of the drawings, like characters of reference designate the 30 same parts.

Figure 1 is a sectional elevation of a ventilator constructed in accordance with my invention,

Fig. 2 is a rear end elevation, and

Fig. 3 is a front end view.

In the drawings, 1 represents a conical funnel arranged horizontally. Within the funnel is a cylindrical shell or chamber 2 of uniform diameter, which is open at its rear 40 end 3 and terminates short of the smaller end of the funnel, while its other end terminates short of the larger end of the funnel and is closed by a cone 4. Extending downwardly from the cylindrical shell 2 is a neck 45 5, which passes through an opening in the lower side of the funnel 1 and is fixed thereto in such a position as to support said cylindrical shell in central spaced relation to the funnel. The neck 5 is rotatably 50 mounted over the end of the pipe 6, which extends through and is fixed to the roof of a building to be ventilated. For rotatably supporting said neck and the parts carried thereby, an upright stationary shaft 7 is 55 fixed at 8 to a bridge 9, which is arranged

crosswise of the pipe 6 and fastened to the sides thereof at 10. The upper end of the shaft 7 is provided with a conical bearing 11, for receiving a pivotal pin 12 carried by a semicircular piece of channel iron 13, 60 which is secured to the upper inner side of the cylindrical shell 2. A guide 14 fixed to the neck 5 at 15, and a similar guide 16 fixed to the pipe 6 at 17 in which the shaft 7 is loosely mounted, serve to maintain the 65 rotatable part of the ventilator in a vertical position. The usual vane 18 carried by the conical funnel 1 is employed for turning the ventilator.

As the wind strikes the cone 4, it is directed outwardly to the larger or front end of the funnel 1, and as the funnel tapers around the cylindrical shell 2, the outlet is contracted, which causes the air to leave at a greater velocity than it entered. This 70 75 produces siphonic action at the open end 3 of the cylindrical shell 2 and naturally exhausts air from the neck 5 and the pipe 6. To further increase the velocity of the air for obtaining greater siphonic action, a plurality of openings 19 are provided in the walls of the cylindrical shell 2, and the openings are covered by inclined pockets 20 having open front ends 21 and closed rear ends 22. As the air enters the open ends of 80 85 the pockets, it is directed through the openings 19, and this produces increased velocity of the air at the open end of the cylindrical shell. The openings are made tapering and larger toward their rear edges to deliver a 90 greater volume of air nearer the open end 3 of the cylindrical shell 2, and thereby create greater siphonic action.

By constructing a ventilator as disclosed, the velocity of the air currents passing horizontally therethrough will be increased and then further stimulated for producing siphonic action and thereby efficiently exhausting air through a vertical pipe for ventilating a building. It will be understood 95 100 that slight changes in the design may be made without departing from the principle of the invention.

Having fully described my invention, what I claim is:

1. In a ventilator, a funnel, a shell arranged longitudinally within the funnel in spaced relation thereto forming an air passage between the two, the shell having a closed end, a neck extending from the shell 110

- through the wall of the funnel for establishing communication from the outside to the inside of the shell, the wall of the shell being provided with openings, pockets covering the openings for directing air from between the funnel and the shell through the openings, substantially as described.
2. In a ventilator, a funnel, a shell arranged longitudinally within the funnel in spaced relation thereto forming an air passage between the two, the shell having an open end and a closed end, the open end of the shell terminating short of the open end of the funnel, a neck extending from the shell through the wall of the funnel for establishing communication from the outside to the inside of the shell, the wall of the shell being provided with openings near its open end, pockets covering the openings, and the pockets having an open end for receiving air entering between the funnel and the closed end of the shell, substantially as described.
3. In a ventilator, a funnel, a shell arranged longitudinally within the funnel in spaced relation thereto forming an air passage between the two, the shell having an open end and a closed end, the open end of the shell terminating short of the open end of the funnel, a neck extending from the shell through the wall of the funnel for establishing communication from the outside

to the inside of the shell, the wall of the shell being provided with openings near its open end, the openings being tapering and larger near the open end of the shell, pockets covering said openings, the pockets being inclined from the inner side of the funnel to the outer side of the shell, and the larger ends of the pockets being open for receiving air entering between the funnel and the closed end of the shell, substantially as described.

4. In a ventilator, a conical funnel, a cylindrical shell arranged longitudinally within the funnel in spaced relation thereto forming an air passage between the two having a smaller outlet than inlet, the cylindrical shell having an open end and being closed at the inlet end of the funnel, the open end of the shell terminating short of the open end of the funnel, a neck extending from the cylindrical shell through the wall of the funnel for establishing communication from the outside to the inside of the cylindrical shell, the wall of the cylindrical shell being provided with openings near its open end, pockets covering the openings, and the pockets having an open end for receiving air entering the inlet end of the funnel, substantially as described.

In testimony whereof I affix my signature.

FRANK E. CRAMPTON.
